UNITED STATES PATENT OFFICE

EMORY GLENN SIMPSON, OF DETROIT, MICHIGAN, ASSIGNOR TO TERNSTEDT MANUFACTURING COMPANY, OF DETROIT, MICHIGAN, A CORPORATION OF MICHIGAN

CURTAIN ROLLER

Application filed December 26, 1929. Serial No. 416,393.

This invention relates to a curtain roller. It is the object of this invention to present a curtain roller that is silent in action, that is, both while the curtain is being raised and 5 when it is being lowered and that will hold the curtain in any raised or lowered position desired.

In the drawings:

Fig. 1 is a longitudinal section of the curtain roller assembly.

Fig. 2 is a section along the line 2—2 of Fig. 1.

Fig. 3 is a section along the line 3—3 of Fig. 1.

15 Fig. 4 is a section along the line 4—4 of Fig. 1.

Figs. 5, 6, and 7 are sections along the lines 5—5, 6—6, and 7—7 of Fig. 1.

Fig. 8 is an end elevation of the curtain 20 roller assembly.

Figs. 9 to 15 inclusive are perspective views of the left hand side of Fig. 1 showing the various parts therein disclosed on a larger scale and in spaced apart position in the 25 relation of mounting.

Referring more particularly to the drawings it will be noted that the curtain roller 1 is mounted upon the brackets 2 and 3. The curtain roller 1 may be made of a tubular 30 sheet of metal having a longitudinal lock seam 4. The ends of the tube, after the internal mechanism which will be described below has been inserted, are closed by means of the slotted discs 5. The roller 1 is provided with the projecting lugs 6 which are passed through the slots 7 in the discs 5 and then turned over to securely fix the discs to the ends of the roller 1. The roller 1 is 35 rotatively mounted upon two shafts 8 and 9. Since preferably only one end of the roller is provided with a clutch mechanism, the shaft 9, which is non-rotatively fixed in the socket 10 of the bracket 3, projects through an opening 11 in the disc 5 to rotatively support the roller 1. The roller 1 has fixed in the end thereof the cylindrical container 12 which encloses a felt cylinder 13 having a central opening 14 for reception of the shaft 40 9. The felt packing cylinder 13 permits easy

rotation of the roller 1 about the shaft 9 and serves as a silencer.

The other roller supporting shaft 8 is non-rotatively fixed in the socket 15 of the bracket 2. This shaft 8 at the innermost end is supported in spaced relation with the inside of the roller by means of the felt packing cylinder 16 which serves as a bearing when the roller is rotated about the shaft. The other end of the shaft 8 has rotatively mounted thereon the bearing member 17. This bearing member 17, as shown in Fig. 4, has a recess 18 which fits about the lock seam 4 thereby locking the roller 1 to the bearing 17 so that the bearing will rotate about the shaft 8 with the roller 1. The roller has the pressed-in lugs 19 which limit the inward movement and properly position the bearing member 17. The bearing member 17 has a tubular projection 20 to which is fixed one end of the roller-actuating coil spring 21. The coil spring 21 is carried by the shaft 8 and the inner-end of the coil spring 21 is fixed to the shaft 8 as at 22.

The bracket 2 has the arcuate rim 23 which cooperates with the recess 24 of the bracket 2 to provide a suitable housing for the clutch mechanism which is entirely concealed. The arcuate rim 23 carries the lug 25 which has the L-shaped socket recess 26, which receives the end 27 of the coil clutch spring 28. The disc 5 has a central aperture for reception of the clutch drum 29 which has the collar 30 spaced from one end of the drum. This end of the drum is projected through the opening in the disc 5 and then spun over as at 31 to securely fix the clutch drum 29 to the disc 5. The clutch drum carries the coil spring 28 the inner-diameter of which is normally a little less than the outer-diameter of the clutch drum 29. In practice it has been found that it takes more than one coil in the locking clutch spring to hold the roller against the torque of the roller spring. Hence, the coil spring 28 is provided with a plurality of coils.

The clutch drum is provided with a circumferential groove in which is rotatively mounted the release trigger 32, the end of the clutch drum being spun over as at 33 to hold

the trigger 32 in position upon the clutch drum 29. The trigger 32 is substantially L-shaped in cross section. The one part 34 of the trigger 32 which extends parallel to the shaft 8 has an opening therein through which the end 35 of the coil spring is projected. The other end of the trigger extends perpendicularly to the longitudinal axis of the shaft 8 and is provided with a suitable opening 36 which is arranged to receive a cord 37, the cord being passed through the opening 38 in the bracket 2. The opening 36 in the release trigger 32 is normally spaced from and out of alignment with the opening 38 in the bracket 2.

In operation when the shade is lowered the roller rotates in the direction of the arrow 39, that is, in a clockwise direction. Since normally the internal diameter of the clutch spring 28 is substantially the same as the outer diameter of the clutch drum 29 there will be but a very little frictional engagement between the drum and the clutch spring as the curtain roller is rotated to lower the curtain. Further, since the rotation of the drum in clockwise direction tends likewise to move the spring 35 in a clockwise direction there is a tendency to expand the coil spring 28. At the same time the end 27 of the clutch spring is held against clockwise rotation by the socket 26 in the annular rim 23 of the bracket 2. This likewise tends to expand the coil spring and thereby reduces the frictional engagement between the drum and the clutch spring to practically nothing; that is, the frictional engagement between the clutch drum and the coil spring is just sufficient to nicely and easily permit the drawing down of the shade. As the shade is being drawn the curtain roller spring 21 is being wound up since one end of the coil spring 21 is fixed to the bearing 17 which rotates with the roller 1 whereas the other end of the coil spring is fixed to the shaft 8 which does not rotate owing to its fixed engagement in the socket 15 of the bracket 2.

When it is desired to raise the shade, the operator pulls the cord 37. Since the opening 36 in the release trigger is normally out of alignment with the opening 38 in the bracket 2, the cord moves the release trigger 32 from the position shown in the full lines (Fig. 2) to the position indicated in the dotted lines. As the trigger 32 is rotated clockwise about the drum it likewise moves the spring end 35 to the position indicated in the dotted lines (Fig. 2) and since at the same time the end 27 of the clutch spring has remained stationary in the socket 26 the clutch spring 28 is expanded. This expansion of the clutch spring 28 reduces the frictional engagement of the clutch spring with the drum 29 sufficiently to permit the torque of the curtain roller spring 21 to overcome the light frictional resistance of the clutch spring with the

clutch drum 29 and thereby rotate the roller 1 in a counter clockwise direction to roll up the curtain. The instant that the pull on the cord 37 is released, the end 35 of the coil spring moves in a counter clockwise direction and the clutch spring 28 contracts and engages the clutch drum 29 with sufficient friction to overcome the torque of coil spring 21 and stop the curtain roller in whatever position it happens to be. The wrapping action of the spring helps to lock the roller in addition to the normal tendency of the spring against the clutch drum. This wrapping action is very important in that the greater the pressure the tighter the spring wraps itself about the drum.

It is evident from the above description that I have here produced a window curtain roller that has obviated the necessity of the noisy pawl and ratchet type of locking mechanism, that is noiseless in operation, and that can be raised or lowered to any desired position.

What I claim is:

1. A curtain roller comprising in combination a shaft, a roller rotatively mounted on the shaft, support means for holding the said shaft non-rotatively, a coil clutch spring arranged to directly clutch the roller, and release trigger means associated with the coil spring whereby the said spring may be placed in clutched or unclutched relation with the said roller when the trigger means are actuated.

2. A curtain roller comprising in combination a shaft, support means for non-rotatively supporting the said shaft, a roller rotatively mounted on the said shaft, a spring having one end fixed to the shaft and the other end to the roller to provide a torque for rotating the roller, a clutch spring operatively associated with the roller to directly clutch the same and having one end secured to the shaft support means, and release trigger means operatively connected to the other end of the clutch spring whereby the trigger means may be pivoted to expand the said clutch spring from clutching relation with the said roller to permit the main spring to rotate the said roller.

3. A curtain roller comprising in combination a shaft, support means for non-rotatively supporting said shaft, a curtain roller mounted on the said shaft, a drum fixed to the said curtain roller, a coil spring mounted on the said drum in clutching relation therewith and having one end fixed to the shaft support means, a main spring having one end fixed to the roller and the other end fixed to the shaft to provide a turning torque for the roller, a trigger rotatively mounted on the said drum and having one end operatively connected with the other end of the coil spring whereby the trigger may be pivoted to expand the coil spring to disengage it

from clutching relation with the said drum to permit the main spring to rotate the said curtain roller.

4. A curtain roller comprising in combination a shaft, support means for non-rotatively supporting the said shaft, a tubular curtain roller having one end closed by a centrally apertured disc, spring torque producing means connected to the said roller and the said shaft, a clutch drum rotatively mounted on the said shaft and secured to the said disc in the said aperture, a clutch spring having a plurality of convolutions mounted on the said drum in clutching relation therewith and with one end fixed to the said shaft support, a trigger rotatively mounted on the said drum and having one end operatively connected to the other end of the clutch spring whereby the trigger may be pivoted about the said clutch drum to expand the said clutch spring to permit the said spring means to rotate the said roller.

5. A curtain roller comprising in combination a bracket having an aperture, a shaft non-rotatively mounted on the said bracket, a roller having a drum portion rotatively mounted on the said shaft, spring torque producing means operatively connected to the roller and the said shaft, a coil spring mounted on the said drum in clutching relation therewith and having one end free and the other end secured to the said bracket, a trigger rotatively mounted on the said drum and having one end connected to the free end of the spring and the other end out of alignment with the aperture in the said bracket, and a cord arranged to be secured to the end of the trigger and pass through the opening in the said bracket whereby said cord may be pulled to actuate the trigger and release the clutch spring from clutching engagement with the said clutch drum to permit the said spring torque means to rotate the curtain roller.

6. A curtain roller comprising in combination of a fixed shaft, support means for supporting the said shaft, a roller having a hub portion rotatively mounted on the said shaft, a coil spring having a plurality of convolutions mounted about and in clutching relation with the hub portion and having one end fixed to one of the above stationary members and the other end free, and means operatively connected to the free end of the spring for expanding the spring out of clutching relation with the said hub portion of the roller to permit rotation of the roller about the shaft.

In testimony whereof I affix my signature.
10 EMORY GLENN SIMPSON.
